UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING APPARATUS

Application filed January 11, 1929. Serial No. 331,839.

This invention relates to mining apparatus and more particularly to coal mining apparatus of the wheel mounted type adapted to operate from the mine trackway.

5 An object of this invention is to provide an improved mining apparatus. Another object is to provide an improved coal mining apparatus of the wheel mounted type adapted to operate from the mine trackway and having improved adjustable kerf cutting mechanism whereby a series of cuts in the coal face in a plurality of intersecting planes may be made. Still another object is to provide an improved coal mining apparatus of the combined vertical and horizontal cutter type having improved and simplified means for adjusting the cutter into its different operative positions. A further object is to provide an improved coal mining apparatus of the type adapted to insert a series of horizontal and vertical or shear cuts in the coal face having an improved adjustable mounting for the cutter and improved means for adjusting the mounting.

15 20 25 Still another object is to provide in an apparatus of the aforesaid type improved means for adjusting the cutter into positions lying in different planes and for swinging the cutter to effect its cutting function, together with improved and simplified means for actuating the cutter in its several adjusted positions. Yet another object of this invention is to provide a mining apparatus of the aforesaid type having improved means for propelling the apparatus along the mine trackway during the cutting operation and transport of the apparatus about the mine. A still further object of this invention is to provide in a mining apparatus of the aforesaid type an improved, simplified, and exceedingly compact general arrangement of parts whereby the apparatus may be operated with facility and expeditiously in mines having narrow entries and low headroom. These and other objects and advantages of this invention will, however, hereinafter more fully appear.

50 In the accompanying drawings there is shown for purposes of illustration one em-

bodiment which the invention may assume in practice.

In these drawings,—

Fig. 1 is a top plan view of the improved mining apparatus.

55

Fig. 2 is a side elevational view of the mining apparatus shown in Fig. 1.

Fig. 3 is a central longitudinally extending vertical sectional view taken substantially on line 3—3 of Fig. 1, with parts 60 shown in elevation.

Fig. 4 is a central longitudinally extending vertical sectional view partially in elevation taken substantially on line 4—4 of Fig. 1.

65

Fig. 5 is a transverse vertical sectional view taken substantially on line 5—5 of Fig. 2.

Fig. 6 is a detail sectional view taken on line 6—6 of Fig. 3, and illustrating the transmission chain lock.

70

Fig. 7 is a transverse vertical sectional view taken substantially on line 7—7 of Fig. 2, with parts shown in elevation.

Fig. 8 is a detail sectional view taken on line 8—8 of Fig. 7.

75

Fig. 9 is a transverse vertical sectional view taken substantially on line 9—9 of Fig. 2, with parts shown in elevation.

Fig. 10 is an enlarged horizontal sectional view illustrating the details of the plural speed transmission mechanism.

Fig. 11 is a transverse vertical sectional view taken substantially on line 11—11 of Fig. 10.

85

Fig. 12 is a detail sectional view taken on line 12—12 of Fig. 10.

In this illustrative embodiment of the invention there is shown a coal mining apparatus of the wheel mounted type adapted to operate from the mine trackway and generally comprising a wheeled truck 1 having usual wheels 2 adapted to run along a mine trackway 3. Mounted on and suitably rigidly fixed to the truck 1 is a low compact machine frame or body 4 carrying at its forward end improved adjustable kerf cutting mechanism generally designated 5, and housing within its intermediate portion a motor 6 adapted to effect drive of the vari-

106

ous devices of the apparatus in either of opposite directions. Housed within the rear end of the frame 4 and driven from the motor 6 is a transmission mechanism 7 for driving the truck wheels and for effecting adjustment of the kerf cutting mechanism, the motor also actuating the kerf cutting mechanism. As hereinafter described the kerf cutting mechanism is adjustable into 10 vertical, horizontal, and intermediate planes and is swingable transversely in its plane, improved means being provided for adjusting the cutting mechanism and for swinging the cutter.

15 Referring more particularly to the improved kerf cutting mechanism 5 it will be noted that the motor 6 is herein preferably of the electric reversible type having its armature shaft 8 horizontally disposed and 20 extending longitudinally of the apparatus. As shown in Fig. 3, the forward end of the armature shaft 8 has rigidly fixed thereto and rotatable therewith a sleeve-coupling 9 journaled in a ball bearing 10 suitably supported by the front motor head. The coupling 9 is splined at 11 to an alined coupling shaft 12. The forward end of the shaft 12 is keyed at 13 to an alined shaft 14 journaled in a ball bearing 15 supported by a 25 forwardly projecting sleeve-like bearing portion 16 herein formed integral with a frame member 17 rigidly fixed to the casing of the motor 6, the bearing portion 16 of the frame surrounding the alined shafts 12 and 14. The shaft 14 has herein preferably formed integral therewith a bevel pinion 18 meshing with a bevel gear 19 herein formed integral with a transverse shaft 20 journaled in spaced alined ball bearings 21 30 suitably supported within a rotatable cutter head 22. The rotatable cutter head 22 has a rearwardly extending sleeve-like bearing portion 23 encircling the bearing portion 16 of the frame and journaled on the bearing 35 portion 16 for rotation about a longitudinal axis, herein coincident with the axis of the motor, in a roller bearing 24 and a ball bearing 25, the latter being held in position by a retaining ring 26. It will be noted that 40 the roller bearing 24 and ball bearing 25 are arranged in longitudinal spaced relation a substantial distance apart, thereby forming an exceedingly stable support for the rotatable cutter head 22. The shaft 20 has 45 also formed integral therewith a spur pinion 27 meshing with a spur gear 28 journaled on ball bearings 29 supported by a transverse main cutter driving shaft 30. The shaft 30 has keyed thereto at 31 a cutter chain drive sprocket 32 engaging and 50 driving a cutter chain 33 mounted for orbital movement on the margin of an elongated plane cutter bar 34. The rear end of this cutter bar is provided with an annular bearing portion 35 mounted for ro-

tative movement about the axis of the shaft 30 on a bearing sleeve 36 supported on the projecting cylindrical portion 37 of the cutter head frame. The bearing portion 35 for the cutter bar is rigidly secured by screws 38 to a member 39 in turn secured by screws 40 to an annular bearing plate 41. The bearing plate 41 engages a bearing sleeve 42 supported on a radial flange 43 projecting outwardly from the frame portion 37. It will thus be seen that the parts 36, 39, 41, 42, and 43 form a pivotal mounting for the cutter bar. The bearing portion 37 is formed integral with a frame section 44 detachably secured by screws 45 to the main cutter head frame. The frame section 44 has a cylindrical portion 46 within which a cylindrical portion 47 of the main cutter head frame projects. As shown, the hub portion of the spur gear 28 is provided with clutch teeth 50 interlocked with clutch teeth 51 formed on a sleeve-like clutch member 52 supported by the shaft 30. Surrounding the clutch member 52 is a clutch member 53 clutched at 54 to a driving sleeve 55 keyed at 56 to the shaft 30. Surrounding the clutch members 52, 53 is a shiftable clutch member 57 having internal clutch teeth engaging the clutch teeth on the member 52 and connectible to the clutch teeth 50 on the member 53. Slidably mounted in a bore 58 formed within the projecting cylindrical portion 47 of the main cutter head frame is a clutch shipper member 59 connected to the clutch member 57. The means for shifting the clutch member 57 into and out of engagement with the clutch teeth on the clutch member 53 herein comprises (as indicated in dotted lines in Fig. 3) a lever 60 pivoted at 61 on the main cutter head frame and pivotally connected at 62 to upstanding ears formed integral with the clutch shipper member 59. The opposite end of the lever 60 is pivotally connected at 63 to a link 64 in turn pivotally connected at 65 to a crank or pivoted arm 66 secured to a transverse operating shaft 67. As shown in Figs. 1 and 2, the operating shaft 67 has secured thereto at its opposite ends at opposite sides of the cutter head 110 suitable operating handles 68. Again referring to the cutter chain driving mechanism it will be noted that the shaft 30 is journaled in a ball bearing 70 supported by the frame section 44. Also supported by 115 the frame section 44 is a packing carrying ring 71 engaging the hub of the cutter chain sprocket 32 and thereby preventing access of detrimental foreign matter to the rotating parts. From the foregoing it will be 120 evident that when the clutch member 57 is shifted into the position shown in Fig. 3 and the clutch members 52 and 53 are connected the cutter chain sprocket 32 may be 125 driven from the motor through bevel gear 130.

ing 18, 19, spur gearing 27, 28, and the main cutter driving shaft 30 and that the cutter chain may be connected to or disconnected from the motor at will. The improved mechanism for rotating the head about its axis and for swinging the cutter bar about its pivotal axis will hereinafter be described.

The improved transmission mechanism 7 for driving the truck wheels to effect propulsion of the apparatus bodily along the mine trackway at a slow cutting speed and at a higher transport speed herein comprises a spur pinion 72 rigidly fixed to the rear end of and rotatable with the armature shaft 8 of the motor. This pinion meshes with an intermediate gear 73 fixed to a horizontal shaft 74 suitably journaled within the machine frame. This gear 73 meshes with a spur gear 75 fixed to a parallel shaft 76 likewise journaled within the machine frame. Herein formed integral with the shaft 76 is a bevel pinion 77 meshing with a bevel gear 78 rigidly fixed to a transverse horizontal shaft 79 suitably journaled on the machine frame. Suitably secured to the shaft 79 is a gear 80 meshing, as shown in Fig. 12, with a spur gear 81 fixed to a horizontal shaft 82 arranged parallel with and above the shaft 79 and likewise journaled on the frame. The shafts 79, 82 have respectively secured thereto intermediate their ends fast and slow speed worms 83 and 84 meshing respectively with worm wheels 85 and 86 coaxially arranged and rotatable about a vertical axis. Coaxially arranged with the worm wheels 85, 86 is a vertical shaft 87 carrying a spur pinion 88. Carried within the worm wheels 85, 86 respectively are friction clutches 89 and 90 of a well known design and these clutches are adapted to be selectively applied by suitable operator-controlled pivoted shipper mechanism 91 to effect drive of the spur pinion 88 at a slow speed in one direction and at a fast speed in the opposite direction. The spur pinion 88 meshes with a large spur gear 92 keyed to a vertical shaft 93 suitably journaled on the frame of the machine. As similar plural speed worm gearing and the friction controlling clutches therefor, together with a similar type of operator-controlled shipper mechanism for the clutches, are clearly described in my copending application, Ser. No. 136,446, filed Sep. 20, 1926, further detailed description of the same is herein submitted to be unnecessary.

Referring more particularly to Fig. 4 it will be noted that the large spur gear 92 meshes with a spur gear 94 keyed to a vertical shaft 95 arranged at the rear of and parallel with the shaft 93. The shaft 95 is journaled in ball bearings 96 supported by a housing 97 rigidly secured to the rear

end of the machine frame 4 and housing the reversible transmission mechanism for driving the truck wheels. The lower end of the shaft 95 has keyed thereto a bevel gear 98 meshing as shown in Fig. 7, with oppositely rotating reverse bevels 99 and 100. The reverse bevels are respectively journaled on bearing sleeves 101 supported by a transversely extending horizontal hollow main driving shaft 102 journaled in ball bearings 103 suitably carried by the housing 97. In this instance, the hub portions of the bevel gears 99 and 100 are respectively provided with clutch teeth 104, 105 which are selectively connectible to clutch teeth 106 carried by the shaft 102. A shiftable clutch member 107 is employed for alternatively connecting the clutch teeth on the reverse bevels to the clutch teeth on the shaft. This clutch member is adapted to be shifted axially in opposite directions by a shipper yoke 108 fixed to a horizontal operating shaft 109 carrying at its rear end a suitable operating lever 110. It will thus be seen that one or the other of the reverse bevels 99, 100 may be connected to the shaft 102 to thereby effect rotation of the latter in one direction or the other as desired. Fixed to one end of the shaft 102 is a clutch member 111 having clutch teeth engaging the clutch teeth of a shiftable clutch member 112 secured to a transverse operating rod 113 extending axially through the hollow shaft 102. As shown in Fig. 8, this rod 113 carries spring pressed plungers engageable with spaced notches in the shaft 102 for maintaining the rod 113 in its different adjusted positions. An operating handle 114 secured to the rod 113 is employed for shifting the clutch member 112 axially to bring the teeth thereof into engagement with clutch teeth 115 formed integral with a chain driving sprocket 116. This sprocket 116 is journaled on a bearing sleeve also supported by the transverse shaft 102 and is connected by an endless chain 117 (see also Fig. 2) to a sprocket 118 suitably fixed to the rear axle of the truck. The axles for the front and rear truck wheels are connected together by a chain and sprocket connection 119. It will thus be evident that when one or the other of the reverse bevels 99, 100 is connected to the shaft 102 and when the clutch member 112 is shifted to connect the clutch members 111, 115 and upon suitable application of the speed controlling frictions 89, 90 the truck wheels may be driven in one direction or the other at either a slow or a relatively high speed.

The improved mechanism for effecting rotation of the cutter head and for swinging the cutter bar about its pivot will now be described. As shown in Fig. 7, the shaft 102 has fixed thereto at the end thereof opposite from the clutch member 111 a simi-

lar clutch member 120 having clutch teeth 121 connectible by a shiftable clutch member 122 to clutch teeth 122 formed on the hub of a chain driving sprocket 123. An operating handle 124, similar to the handle 114 for the clutch member 112, is employed for shifting the clutch member 121 into its connected or released position. The chain driving sprocket 123 drives through a chain and sprocket connection 125 a similar chain and sprocket connection 126 which is connected to a chain sprocket 127 (see Fig. 9) keyed to a transversely extending horizontal shaft 128 journaled in ball bearings 129 suitably carried within the frame section 17 of the machine body. This shaft has herein preferably formed integral therewith a worm 130 meshing with a worm wheel 131 surrounding the axial line of the rotatable cutter head and rigidly fixed by keys 132 to a chain sprocket 133, the worm wheel being journaled on the sleeve-like bearing portion 23 of the cutter carrying head 22. As illustrated, engaging this chain sprocket 133 is an endless flexible transmission element herein in the form of a loose-link chain 134 and constituting the final transmission element for effecting head rotation and for swinging the cutter bar about its pivotal axis. The pitch line speed of this chain is appropriate for bar swing, at a cutting speed. The chain 134 passes over the upper surface of the chain sprocket 133 around the angularly disposed guide sprockets 135 offset laterally from the head axis and suitably journaled on the cutter head frame, the chain extending forwardly around these guide sprockets through openings 136 formed in the cutter head frame 40 and forwardly around an annular groove 137 formed on the external periphery of the member 39 secured to the cutter bar 34. Means is also provided for locking the rotatable cutter head to the relatively stationary machine body and herein comprises a stationary locking ring 138 secured at 139 to the sleeve-like bearing portion 16 of the frame section 17. Engageable with the cylindrical outer surface of the locking ring 138 are a plurality of toothed locking members 140 having adjusting screws 141 threadedly connected to the head frame. It will thus be seen that when the screws 141 are screwed inwardly the locking members 140 rigidly hold the rotatable cutter head against rotation relative to the machine frame. Means is also provided for locking the endless chain 134 to the member 39 secured to the cutter bar and herein comprises, as shown in Figs. 3 and 6, a slidable locking member 142 having chain engaging teeth 143 and carried by a projecting boss 144 herein formed integral with the member 39. The locking member 142 is held against displacement from the boss by means of pins 145 engaging opposite sides thereof and secured to the boss. Threadedly connected within the boss 144 is an adjusting screw 146 for effecting adjustment of the locking member 142. Also threadedly connected within the boss 144 is an adjusting screw 147 engageable with a toothed locking member 148 engageable with the cylindrical surface of a flange 149 formed integral with the frame section 44 secured to the main cutter head frame. From the foregoing description it is evident that when the adjusting screws 146, 147 are adjusted to move their respective locking members inwardly, the endless chain 134 is held against movement relative to the member 39 and the latter is in turn rigidly locked against rotative movement relative to the cutter head frame. Upon release of the locking members 140, and when the clutch 120, 121, 122 is connected, the chain sprocket 133 may be rotated by the worm wheel 131 causing the sprocket 133 to act on the endless chain 134 which is then held against movement relative to the cutter head and as a result the cutter head is rotated about its axis, the pull of the chain 134 on the laterally located guide sprockets 135 carried by the cutter head effecting rotation. When the locking member 148 is released, the locking member 142 moved into its locking position connecting the chain 134 to the cutter bar 34, and the locking members 140 are moved into their locking position thereby holding the cutter head against rotation, upon rotation of the sprocket 133 the endless chain 134 is drawn in thereby effecting swinging movement of the cutter bar about its pivot relative to the cutter head frame. Upon suitable application of the friction speed controlling clutches 89, 90 and the reverse controlling clutch 107 it is obvious that the cutter head and cutter bar may be moved about their respective pivotal axes at either a fast speed or a slow speed in opposite directions. It will be noted that the rear truck axle is provided with a frictional braking device 150 (see Fig. 1) having usual controlling means including an operating lever 151 and this braking device is adapted to hold the apparatus stationary at certain times during the cutting operation and to control movement of the apparatus along an inclined trackway.

The operation of the improved mining apparatus is as follows: The mining apparatus is propelled along the mine entry by the truck wheels at a fast speed under the control of the fast speed friction clutch 89. It will be understood that at that time the reverse bevel 99 is connected to the shaft 102 by the clutch member 107 and that the clutch member 112 is in its connected position, the truck wheels being driven at a fast transport speed by the motor pinion 72 through 130

gearing 73, 75, bevel gearing 77, 78, worm gearing 83, 85, spur gearing 88, 92, 94, bevel gearing 98, 99, shaft 102, and chain and sprocket connections 116, 117, 118, and 119.

5 If it is desired to propel the apparatus rearwardly at a high speed the bevel gear 99 is disconnected from the driving shaft 102 and the clutch member 107 slid into engagement with the clutch teeth on the gear 100 thereby

10 reversing the drive. When the working face is reached and it is desired to insert the horizontal cut in the coal face the locking member 148 is moved into its released position, and the locking member 142 moved into its

15 locking position connecting the chain 134 to the cutter bar 34, and the cutter head is rigidly locked to the machine frame by the locking members 140. The clutch 120, 121, 122 is then connected and the reverse bevel

20 99 is connected to the shaft 102 by the clutch 107 and upon suitable application of the fast speed friction clutch 89 the cutter bar 34 is swung transversely in its plane to a point adjacent the right hand rib, the bar being

25 swung by the motor at a fast bar positioning speed through spur gearing 72, 73, 75, bevel gearing 77, 78, worm gearing 83, 85, spur gearing 88, 92, 94, bevel gearing 98, 99, shaft 102, chain and sprocket connections

30 123, 125, 126, and 127, worm gearing 130, 131, the sprocket 133, and the endless chain 134 connected to the cutter bar 34. The cutter bar is thereafter locked against movement relative to the cutter head frame by

35 the locking member 148, the lock 142 and clutch 121 are released, and the clutch 112 is then connected and upon connection of reverse bevel 100 and application of the slow speed friction clutch 90 the apparatus is

40 moved forwardly bodily along the trackway at a slow cutting speed through the slow speed worm gearing 84, 86 of the transmission, thereby effecting sumping of the cutter bar within the coal. The brake 150 is

45 then set and the locking member 148 is moved into its released position, the locking member 142 moved into its locking position, and upon the connection of clutch 121 the cutter bar is swung through the slow speed

50 worm gearing 84, 86 of the transmission and the connections including sprocket 133 and chain 134 about its pivot at a cutting speed to effect a transverse swinging cut, the brake 150 thereafter being released. The cutter

55 bar is thereafter locked to the cutter head frame and the apparatus propelled bodily rearwardly along the trackway at a cutting speed to effect its withdrawal cut. If it is desired to insert a vertical or shear cut in the

60 coal face the locking members 142, 148 are moved into their locking position and the locking members 140 are released and upon connection of the clutch 121 with clutch 89 loaded and bevel 99 driving, the chain

65 sprocket 133 acts on the chain 134 which is

then fixed to the cutter head thereby causing the cutter head to be rotated about its axis, the pull of the chain on the laterally located guide sprockets 135 carried by the cutter head effecting head rotation. When the cutter bar has assumed a position in a vertical plane, i. e., in its shearing position, the bar is sumped into the coal, swung downwardly, and then withdrawn from the coal in a manner substantially similar to that described in connection with the horizontal cut. It will also be noted that the cutter head may be rotated about its axis to position the cutter bar in a plurality of intersecting planes about the head axis, it being possible to position the cutter bar in a vertical plane at either side of the central longitudinal vertical plane of the apparatus or into any intermediate planes about the head axis.

It is also evident that the cutter bar may be swung about its pivot in any of the aforesaid adjusted positions of the cutter head. Other operations and uses of the improved mining apparatus will be clearly apparent to those skilled in the art.

As a result of the invention it will be noted that improved adjustable kerf cutting mechanism is provided whereby the cutter bar may be moved into a plurality of intersecting planes and having improved and simplified driving connections whereby the cutting mechanism may be adjusted and the cutter bar swung about its pivot. It will further be noted that improved plural speed reversible truck driving mechanism is provided whereby the apparatus may be moved along the trackway in either direction at a relatively slow cutting speed or at a relatively high transport speed. This improved truck driving mechanism has associated therewith improved mechanism for adjusting and swinging the cutter bar. It will further be noted that the adjusting means for moving the cutter bar in a plurality of planes and for swinging the cutter bar about its pivotal axis is of an exceedingly simple construction, a single final flexible transmission element being employed instead of the usual geared transmission thereby greatly decreasing the cost and weight of the machine, together with the resultant decrease in repair expense due to the elimination of complicated driving connections.

While there is in this application specifically described one embodiment which the invention may assume in practice, it will be understood that this embodiment is shown for purposes of illustration and that the invention may be modified and embodied in various other forms without departing from its spirit or the scope of the appended claims.

What I claim as new and desire to secure by Letters Patent is:

1. In a mining apparatus, the combination

of a body, a cutter carrying head rotatably mounted on said body and having a pivoted cutter bar mounted thereon, a motor in said body, and mechanism driven by said motor for swinging said bar about its pivot relative to said head in any adjusted position of the latter about its axis comprising a power transmitting member rotatable relative to said head and surrounding the head axis, said member having an annular bearing portion and said head having a circular external peripheral portion which said annular bearing portion surrounds, and operative connections between said rotatable member and said cutting bar for transmitting a swinging force from the former to the latter.

2. In a mining apparatus, the combination of a body, a cutter carrying head rotatably mounted on said body and having a pivoted cutter bar mounted thereon, a motor in said body, and mechanism driven by said motor for rotating said head and for swinging said bar about its pivot relative to said head in any adjusted position of the latter about its axis comprising a power transmitting member rotatable relative to said head and surrounding the head axis, said member having an annular bearing portion and said head having a circular external peripheral portion which said annular bearing portion surrounds, and operative connections between said rotatable member and said head and cutter bar for transmitting a moving force from said member to said head or to said bar.

3. In a mining apparatus, the combination of a body, a cutter carrying head rotatably mounted on said body and having a pivoted cutter bar mounted thereon, a motor in said body, and mechanism driven by said motor for swinging said bar about its pivot relative to said head in any adjusted position of the latter about its axis comprising a power transmitting member rotatable relative to said head and surrounding the head axis, and flexible swinging means connected to said cutter bar and having an intermediate portion engaging said rotatable member for actuation by the latter.

4. In a mining apparatus, the combination of a body, a cutter carrying head rotatably mounted on said body and having a pivoted cutter bar mounted thereon, a motor in said body, and mechanism driven by said motor for rotating said head and for swinging said bar about its pivot relative to said head in any adjusted position of the latter about its axis comprising a power transmitting member rotatable relative to said head and surrounding the head axis, and flexible swinging means connected to said cutter bar and having an intermediate portion engaging said rotatable member for actuation by the latter.

5. In a mining apparatus, the combination

of a body, a cutter carrying head having a portion by means of which it is rotatably mounted on said body and having a pivoted cutter bar mounted thereon, a motor in said body, and mechanism driven by said motor for rotating said head and for swinging said cutter bar about its pivot relative to said head in any adjusted position of the latter about its axis comprising a power transmitting member rotatable relative to said head and surrounding that portion of said head by which said head is rotatably mounted on said body, operative connections between said rotatable member and said cutter bar for transmitting a swinging force from the former to the latter, and means for holding said head against rotation during bar swing.

6. In a mining apparatus, the combination of a body, a cutter carrying head rotatably mounted on said body and having a pivoted cutter bar mounted thereon, a motor in said body, and mechanism driven by said motor for rotating said head and for swinging said cutter bar about its pivot relative to said head in any adjusted position of the latter about its axis comprising a power transmitting member rotatable relative to said head and surrounding the head axis, flexible swinging means connected to said cutter bar and having an intermediate portion engaging said rotatable member for actuation thereby, and means for holding said head against rotation during bar swing.

7. In a mining apparatus, the combination of a body, a cutter carrying head having a portion by means of which it is rotatably mounted on said body and having a pivoted cutter bar mounted thereon, a motor in said body, and mechanism driven by said motor for rotating said head and for swinging said cutter bar about its pivot relative to said head in any adjusted position of the latter about its axis comprising a power transmitting member rotatable relative to said head and surrounding that portion of said head by which said head is rotatably mounted on said body, operative connections between said member and said head and cutter bar for transmitting a moving force from said member to said head or to said bar, and means for holding said cutter bar against swinging movement relative to said head during head rotation.

8. In a mining apparatus, the combination of a body, a cutter carrying head rotatably mounted on said body and having a pivoted cutter bar mounted thereon, a motor in said body, and mechanism driven by said motor for rotating said head and for swinging said cutter bar about its pivot relative to said head in any adjusted position of the latter about its axis comprising a power transmitting member rotatable relative to said head and surrounding the head axis, flexible connections including a flexible element con-

5 nected to said head and bar and having an intermediate portion engaging said rotatable member for actuation by the latter, and means for holding said cutter bar against swinging movement relative to said head during head rotation.

9. In a mining apparatus, the combination of a body, a cutter head rotatably mounted on said body and having a pivoted cutter bar mounted thereon, a motor in said body, and mechanism driven by said motor for rotating said head and for swinging said cutter bar about its pivot relative to said head in any adjusted position of the latter about its axis comprising a rotatable power transmitting member, and a flexible transmission element connected between said member and said head and cutter bar and actuated by said member and adapted to circulate relative to said head and bar when disconnected therefrom, means for operatively connecting said cutter bar to said flexible element, and means for holding said head against rotation during bar swing.

25 10. In a mining apparatus, the combination of a body, a cutter head rotatably mounted on said body and having a pivoted cutter bar mounted thereon, a motor in said body, and mechanism driven by said motor for rotating said head and for swinging said cutter bar about its pivot relative to said head in any adjusted position of the latter about its axis comprising a rotatable power transmitting member, a flexible transmission element connected between said member and said head and cutter bar and actuated by said member and adapted to circulate relative to said head and bar when disconnected therefrom, means for operatively connecting said cutter bar to said flexible element, and means for holding said cutter bar against swinging movement relative to said head during head rotation.

45 11. In a mining apparatus, the combination of a body, a cutter carrying head having a portion by means of which it is rotatably mounted on said body and having a pivoted cutter bar mounted thereon, a motor in said body, and mechanism driven by said motor for rotating said head and for swinging said cutter bar about its pivot relative to said head in any adjusted position of the latter about its axis comprising a power transmitting member rotatable relative to said head and surrounding that portion of said head by means of which said head is rotatably mounted on said body, operative connections between said member and said head and cutter bar for transmitting a moving force from said member to said head or to said bar, means for holding said head against rotation during bar swing, and means for holding said bar against swinging movement relative to said head during head rotation.

12. In a mining apparatus, the combination of a body, a cutter carrying head rotatably mounted on said body and having a pivoted cutter bar mounted thereon, a motor in said body, and mechanism driven by said motor for rotating said head and for swinging said cutter bar about its pivot relative to said head in any adjusted position of the latter about its axis comprising a power transmitting member rotatable relative to said head and surrounding the head axis, flexible connections including a flexible element connected to said head and bar and having an intermediate portion engaging said rotatable member for actuation by the latter, means for holding said head against rotation during bar swing, and means for holding said bar against swinging movement relative to said head during head rotation.

13. In a mining apparatus, the combination of a body, a cutter carrying head rotatably mounted on said body and having a pivoted cutter bar mounted thereon, a motor in said body, and mechanism driven by said motor for alternatively rotating said head and for swinging said cutter bar about its pivot relative to said head in any adjusted position of the latter about its axis comprising a power transmitting member rotatable relative to said head and surrounding the head axis, said member having an annular bearing portion and said head having a circular external peripheral portion which said annular bearing portion surrounds, and operative connections between said rotatable member and said head and cutter bar for transmitting a moving force from said member to said head or to said bar.

14. In a mining apparatus, the combination of a body, a cutter carrying head rotatably mounted on said body and having a pivoted cutter bar mounted thereon, a motor in said body, and mechanism driven by said motor for alternatively rotating said head and for swinging said cutter bar about its pivot relative to said head in any adjusted position of the latter about its axis comprising a power transmission member rotatable relative to said head and surrounding the head axis, and flexible connections including a flexible element connected to said head and bar and having an intermediate portion engaging said rotatable member for actuation by the latter.

15. In a mining apparatus, the combination of a body, a cutter carrying head rotatably mounted on said body and having a pivoted cutter bar mounted thereon, a horizontal motor in said body having its power shaft extending longitudinally of the apparatus, mechanism driven from one end of said motor for actuating said cutter bar, mechanism driven from the opposite end of

said motor for effecting rotation of said head and for swinging said bar about its pivot relative to said head in any adjusted position of the latter about its axis comprising a power transmitting member rotatable relative to said head and surrounding the head axis, and flexible swinging means operatively connected to said head and cutter bar and having an intermediate portion engaging said rotatable member for actuation by the latter.

16. In a mining apparatus, the combination of a body, a cutter carrying head rotatably mounted on said body and having a pivoted cutter bar mounted thereon, a horizontal motor in said body having its power shaft extending longitudinally of the apparatus, mechanism driven from the front end of said motor for actuating said cutter bar, mechanism driven from the rear end of said motor for effecting rotation of said head and for swinging said bar about its pivot relative to said head in any adjusted position of the latter about its axis comprising a power transmitting member rotatable relative to said head and surrounding the head axis, and flexible swinging means operatively connected to said head and cutter bar and having an intermediate portion engaging said rotatable member for actuation by the latter.

17. In a mining apparatus, the combination of a body, kerf cutting mechanism carried thereby including a pivoted cutter bar swingable in a vertical plane to cut a vertical kerf, a motor, and mechanism driven by said motor for swinging said cutter bar about its pivot comprising a power transmitting member disposed adjacent said cutting mechanism and rotatable about a longitudinal axis, and flexible transmission means having portions connected to said bar and an intermediate portion engaging said rotatable member for actuation by the latter.

18. In a mining apparatus, the combination of a body, kerf cutting mechanism carried thereby including a pivoted cutter bar swingable in a vertical plane to cut a vertical kerf, a motor, and constantly operative means driven by said motor for swinging said cutter bar about its pivot in opposite directions comprising a power transmitting member disposed adjacent said cutting mechanism and rotatable about a longitudinal axis, and flexible transmission means having portions connected to said bar and an intermediate portion engaging said rotatable member for actuation by the latter.

19. In a mining apparatus, the combination of a body, kerf cutting mechanism carried thereby including a pivoted cutter bar swingable in vertical or in horizontal planes to cut vertical and horizontal kerfs, a motor, and means driven by said motor for swinging said bar about its pivot comprising a

power transmitting member disposed adjacent said cutting mechanism and rotatable about a longitudinal axis, and flexible swinging means having portions connected to said cutter bar and an intermediate portion engaging said rotatable member for actuation by the latter.

20. In a mining apparatus, the combination of a body, kerf cutting mechanism including a cutter carrying head mounted on said body and having a pivoted cutter bar mounted thereon, a motor, and mechanism driven by said motor for swinging said cutter bar about its pivot relative to said head when said head is held against rotating movement including a power transmitting member rotatable relative to said head and surrounding the head axis, and flexible bar swinging means operatively connected to said head and bar and having an intermediate portion engaging said rotatable member for actuation by the latter.

21. In a mining apparatus, the combination of a body, kerf cutting mechanism carried thereby including a pivoted cutter bar swingable relative to said body, and motor operated devices for effecting bar swing including a rotatable power driven member disposed at the end of said body adjacent said kerf cutting mechanism, a flexible transmission element engaging said rotatable member and actuated thereby and operatively connected to said cutter bar, and means operable at will for disconnecting said cutter bar from said flexible element.

22. In a mining apparatus, the combination of a body, kerf cutting mechanism carried thereby including a pivoted cutter bar swingable relative to said body, and motor operated devices for effecting bar swing including a rotatable power driven member disposed at the end of said body adjacent said kerf cutting mechanism, an endless flexible transmission element engaging said rotatable member and actuated thereby and operatively connected to said cutter bar, and means operable at will for disconnecting said cutter bar from said flexible element.

23. In a mining apparatus, the combination of a body, kerf cutting mechanism carried thereby including a pivoted cutter bar swingable relative to said body, and motor operated devices for effecting bar swing including a rotatable power driven member disposed at the end of said body adjacent said kerf cutting mechanism, a flexible transmission element engaging said rotatable member and actuated thereby and operatively connected to said cutter bar, and means for disconnecting said cutter bar from said flexible element at will.

24. In a mining apparatus, the combination of a body, kerf cutting mechanism carried thereby including a pivoted cutter bar swingable relative to said body, and motor

- operated devices for effecting bar swing including a rotatable power driven member disposed on a horizontal longitudinally extending axis at the end of said body adjacent said kerf cutting mechanism, and an endless flexible transmission element engaging said rotatable member and actuated thereby and operatively connected to said cutter bar.
25. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element operatively connectible to said head and kerf cutter to rotate the former and swing the latter, said kerf cutter being connected to said element at all times during motor operated head rotation by a direct attachment which precludes any relative movement between said element and said kerf cutter, and means for disconnecting said kerf cutter from said element at will and for connecting said kerf cutter to said transmission element irrespective of the position of said transmission element relative thereto.
30. 26. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element operatively connectible to said head and kerf cutter to rotate the former and to swing the latter, said kerf cutter being connected to said element by a direct attachment which precludes any relative movement between said element and said kerf cutter and being held stationary relative to said head at all times during motor operated head rotation, and means for releasing said kerf cutter from said element at will and for connecting said kerf cutter to said transmission element irrespective of the position of said transmission element relative thereto.
35. 27. In a mining apparatus, the combination of a body, kerf cutting mechanism including a cutter head mounted on said body for rotation about a longitudinal axis and a kerf cutter pivotally mounted on said head for swinging movement relative thereto, and motor operated devices disposed wholly at the end of the apparatus adjacent said cutter head for rotating said head and for swinging said kerf cutter including a common transmission element operatively connectible to said head and kerf cutter to rotate the former and to swing the latter, said kerf cutter being connected to said element by a direct attachment which precludes any relative movement between said element and said kerf cutter and being held stationary relative to said head at all times during motor operated head rotation, and devices carried by said kerf cutter for disconnecting said kerf cutter from said element and for holding said kerf cutter against swinging movement relative to said head.
40. 28. In a mining apparatus, the combination of a body, kerf cutting mechanism including a cutter head mounted on said body for rotation about a longitudinal axis and a kerf cutter pivotally mounted on said head for swinging movement relative thereto, motor operated devices for rotating said head and for swinging said kerf cutter including a common transmission element operatively connectible to said head and kerf cutter to rotate the former and to swing the latter, said kerf cutter being connected to said element at all times during motor operated head rotation, said element when so connected being completely immovable relative to said kerf cutter, and said element having movement relative to said head and kerf cutter while said head and kerf cutter remain stationary, and means for operatively connecting said kerf cutter to said transmission element irrespective of the position of said transmission element relative thereto.
45. 29. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element operatively connectible to said head and kerf cutter to rotate the former and to swing the latter, said motor operated devices being operative to effect movement of said transmission element relative to said head and kerf cutter when disconnected therefrom and while maintaining a predetermined relation thereof relative to said head and said kerf cutter being connected to said element at all times during motor operated head rotation, said element when so connected being completely immovable relative to said kerf cutter, and means carried by said head for connecting the latter to or disconnecting the same from said element at will.
50. 30. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element

operatively connectible to said head and kerf cutter to rotate the former and to swing the latter, said motor operated devices being operative to effect movement 5 of said transmission element relative to said head and kerf cutter when disconnected therefrom and while maintaining a predetermined relation thereof relative to said head and said kerf cutter being connected 10 to said element by a direct attachment which precludes any relative movement between said element and said kerf cutter and being held stationary relative to said head at all times during motor operated head rotation, and means carried by said head for 15 connecting the latter to or disconnecting the same from said element at will.

31. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said 25 head and for swinging said kerf cutter including a common transmission element operatively connectible to said head and kerf cutter to rotate the former and to swing the latter, said motor operated devices being 30 operative to effect movement of said transmission element relative to said head and kerf cutter when disconnected therefrom and while maintaining a predetermined relation thereof relative to said head 35 and said kerf cutter being connected to said element at all times during motor operated head rotation by a direct attachment which precludes any relative movement between said element and said kerf cutter, and devices carried by said cutter head and 40 releasable at will for holding the latter against rotation about its axis during swinging of said kerf cutter.

32. In a mining apparatus, the combination of a body, kerf cutting mechanism including a cutter head mounted on said body for rotation about a longitudinal axis and a kerf cutter pivotally mounted on said head for swinging movement relative thereto, and 45 motor operated devices for rotating said head and for swinging said kerf cutter including a common transmission element operatively connectible to said head and kerf cutter to rotate the former and to swing the latter, said motor operated devices being 50 operative to effect movement of said transmission element relative to said head and kerf cutter when disconnected therefrom and while maintaining a predetermined relation 55 thereof relative to said head and said kerf cutter being connected to said element at all times during motor operated head rotation, and devices releasable at will for connecting 60 said kerf cutter to said element by a direct attachment which precludes any relative 65

movement between said element and said kerf cutter and for holding said kerf cutter against swinging movement relative to said head during head rotation.

33. In a mining apparatus, the combination of a body, kerf cutting mechanism including a cutter head mounted on said body for rotation about a longitudinal axis and a kerf cutter pivotally mounted on said head for swinging movement relative thereto, and motor operated devices disposed wholly at the end of the apparatus adjacent said cutter head for rotating said head and for swinging said kerf cutter including a common transmission element operatively connectible to said head and kerf cutter to rotate the former and to swing the latter, said kerf cutter being connected to said element at all times during motor operated head rotation, and devices releasable at will for connecting said kerf cutter to said element by a direct attachment which precludes any relative movement between said element and said kerf cutter and for holding said kerf cutter against swinging movement relative to said head during head rotation, said kerf cutter holding devices being released and said cutter head held against rotation about its axis during swinging of said kerf cutter.

34. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said cutter head and for swinging said kerf cutter, said head rotating devices and said kerf cutter swinging devices including a common flexible transmission element connectible to both said head and kerf cutter, said flexible element being adapted to circulate relative to said head and kerf cutter while said head and kerf cutter are disconnected therefrom.

35. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said cutter head and for swinging said kerf cutter, said head rotating devices and said kerf cutter swinging devices including a common endless flexible transmission element adapted to circulate relative to said head and kerf cutter and connectible to both said head and kerf cutter.

36. In a mining apparatus, the combination of a body, kerf cutting mechanism including a cutter head mounted on said body for rotation about a longitudinal axis and a kerf cutter pivotally mounted on said head for swinging movement relative thereto, and

motor operated devices for rotating said cutter head and for swinging said kerf cutter, said head rotating devices and said kerf cutter swinging devices including a common endless flexible transmission element connectible to both said head and kerf cutter, said endless flexible transmission element being adapted to circulate relative to said head and kerf cutter while said head and kerf cutter remain stationary and operable to effect either head rotation or swinging of said kerf cutter at will.

37. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said cutter head and for swinging said kerf cutter, said head rotating devices and said kerf cutter swinging devices including a power driven rotatable member having its axis alined with the head axis and a cooperating common flexible transmission element to which both said head and kerf cutter are connectible at will, said flexible element being adapted to circulate relative to said head and kerf cutter when disconnected therefrom.

38. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said cutter head and for swinging said kerf cutter, said head rotating devices and said kerf cutter swinging devices including a power driven rotatable member having its axis alined with the head axis and a common endless flexible element adapted to circulate relative to said head and kerf cutter and to which both said head and kerf cutter are connectible at will.

39. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said cutter head and for swinging said kerf cutter, said head rotating devices and said kerf cutter swinging devices including a power driven rotatable member having its axis alined with the head axis and a cooperating common endless flexible transmission element to which both said head and kerf cutter are connectible, said flexible transmission element being adapted to circulate relative to said head and kerf cutter while said head and kerf cutter remain stationary

and operable to effect either head rotation or kerf cutter swing at will.

40. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for effecting head rotation and swinging of said kerf cutter including a rotatable power driven member and a cooperating endless flexible transmission member to which both said head and kerf cutter are connectible, the orbit of said flexible element maintaining a uniformity in shape during head rotation.

41. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for effecting head rotation and bar swing including a rotatable power driven member and a co-operating endless flexible transmission member adapted to circulate relative to said head and kerf cutter and to which both said head and kerf cutter are connectible, the orbit of said flexible element remaining unchanged during swinging of said kerf cutter.

42. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for effecting head rotation and swinging of said kerf cutter including a rotatable power driven member and a cooperating endless flexible transmission member to which both said head and kerf cutter are connectible, the orbit of said flexible element maintaining a uniformity in shape during both head rotation and swinging of said kerf cutter.

43. In a mining apparatus, the combination of a body, kerf cutting mechanism including a kerf cutter pivotally mounted on said body for swinging movement vertically relative thereto to cut a vertical kerf, motor operated devices for effecting bar swing including a rotatable power driven member and a cooperating endless flexible transmission element connected to said member, the orbit of said flexible element remaining unchanged during swinging of said kerf cutter, and means for disconnecting said kerf cutter from said flexible element, said element being adapted to circulate relative to said kerf cutter while disconnected therefrom.

44. In a mining apparatus, the combination of a body, kerf cutting mechanism in-

cluding a cutter head mounted on said body for rotation about a longitudinal axis and a kerf cutter pivotally mounted on said head for swinging movement relative thereto and 5 having cutting appliances thereon, motor operated devices for rotating said head including a gear surrounding the head axis and operatively connected to said head, mechanism driven by said gear for swinging 10 said kerf cutter about its pivot, and means for actuating said cutting appliances while said gear remains stationary.

45. In a mining apparatus, the combination of a body, kerf cutting mechanism including a cutter head mounted on said body for rotation about a longitudinal axis and a kerf cutter pivotally mounted on said head for swinging movement relative thereto and having cutting appliances thereon, motor 15 operated devices for rotating said head including a gear surrounding the head axis and operatively connected to said head, mechanism driven by said gear for swinging said kerf cutter about its pivot, means for 20 connecting said gear to said head, said gear being disconnected from said head during swinging of said kerf cutter, and means for actuating said cutting appliances while said gear remains stationary.

30 46. In a mining apparatus, the combination of a body, kerf cutting mechanism including a cutter head mounted on said body for rotation about a longitudinal axis and a kerf cutter pivotally mounted on said 35 head for swinging movement relative thereto, motor operated devices for rotating said head about its axis including a final transmission element having a pitch line speed appropriate for swinging said kerf cutter 40 at a cutting speed and fixedly connectible to said head to rotate the latter on said longitudinal axis and disposed wholly at the end of the apparatus adjacent and guided on said head, said element when so connected being 45 completely immovable relatively to said head, and mechanism driven by said transmission element operative when said element is disconnected from said head to effect swinging of said kerf cutter.

50 47. In a mining apparatus, the combination of a body, kerf cutting mechanism including a cutter head mounted on said body for rotation about a longitudinal axis and a kerf cutter pivotally mounted on said head 55 for swinging movement relative thereto, motor operated devices for rotating said head about its axis including a final transmission element having a pitch line speed appropriate for swinging said kerf cutter at 60 a cutting speed and fixedly connectible to said head to rotate the latter on said longitudinal axis and disposed wholly at the end of the apparatus adjacent and guided on said head, said element when so connected 65 being completely immovable relatively to

said head, mechanism driven by said transmission element operative when said element is disconnected from said head to effect swinging of said kerf cutter, and means for holding said cutter head against rotation 70 during swinging of said kerf cutter.

48. In a mining apparatus, the combination of a body, kerf cutting mechanism including a cutter head mounted on said body for rotation about a longitudinal axis and a kerf cutter pivotally mounted on said head for swinging movement relative thereto, motor operated devices for rotating said head about its axis including a final transmission element having a pitch line speed 80 appropriate for swinging said kerf cutter at a cutting speed and fixedly connectible to said head to rotate the latter on said longitudinal axis and disposed wholly at the end of the apparatus adjacent and guided on 85 said head, said element when so connected being completely immovable relatively to said head, mechanism driven by said transmission element operative when said element is disconnected from said head to effect 90 swinging of said kerf cutter, and means for holding said kerf cutter against swinging movement relative to said head during head rotation.

49. In a mining apparatus, the combination of a body, kerf cutting mechanism including a cutter head mounted on said body for rotation about a longitudinal axis and a kerf cutter mounted on said head, motor operated devices including a worm wheel 100 encircling the head axis and rotatable relative to said head, and means for connecting said head to said worm wheel to effect head rotation at will.

50. In a mining apparatus, the combination of a body, kerf cutting mechanism including a cutter head mounted on said body for rotation about a longitudinal axis and a kerf cutter pivotally mounted on said head for swinging movement relative thereto, motor operated devices including a worm 110 wheel encircling the head axis and rotatable relative to said head, means for connecting said head to said worm wheel to effect head rotation at will, and means for operatively 115 connecting said kerf cutter to said worm wheel to effect swinging movement of said kerf cutter.

51. In a mining apparatus, the combination of a body, kerf cutting mechanism including a cutter head mounted on said body for rotation about a longitudinal axis and a kerf cutter pivotally mounted on said head for swinging movement relative thereto, motor operated devices including a worm 120 wheel encircling the head axis and rotatable relative to said head, means for connecting said head to said worm wheel to effect head rotation at will, and means for operatively 125 connecting said kerf cutter to said worm 130

wheel to effect swinging movement thereof, said cutter head being held against rotation during swinging movement of said kerf cutter.

- 5 52. In a mining apparatus, the combination of a body, kerf cutting mechanism including a cutter head mounted on said body for rotation about a longitudinal axis and a kerf cutter pivotally mounted on said head for swinging movement relative thereto, motor operated devices including a worm wheel encircling the head axis and rotatable relative to said head, means for connecting said head to said worm wheel to effect head 70 rotation at will, and means for operatively connecting said kerf cutter to said worm wheel to effect swinging movement thereof, said kerf cutter being held against swinging movement relative to said head during 75 head rotation.
53. In a mining apparatus, the combination of a wheeled support adapted to run along a mine trackway, kerf cutting mechanism adjacent the front end of said support including a cutter head mounted on said support for rotation about a longitudinal axis and a kerf cutter mounted on said head, and motor operated devices for effecting head rotation and driving said support 80 wheels including a transverse shaft disposed at the rear of said support, reverse mechanism co-axial with said shaft for effecting drive thereof selectively in opposite directions, mechanism driven by said shaft for 85 driving the support wheels at such speeds, and means for only alternatively connecting said mechanisms in driving relation with said shaft.
54. In a mining apparatus, the combination of a wheeled support adapted to run along a mine trackway, kerf cutting mechanism adjacent the front end of said support including a cutter head mounted on said support for rotation about a longitudinal axis and a kerf cutter mounted on said head, and motor operated devices for effecting head rotation and driving said support 90 wheels including a transverse shaft disposed at the rear of said support, reverse mechanism co-axial with said shaft for effecting drive thereof selectively in opposite directions, plural speed transmission 95 mechanism for effecting rotation of said shaft at either a relatively high speed or a relatively low speed, mechanism driven by said shaft for rotating the head at such speeds, mechanism driven by said shaft for driving the support wheels at such speeds, and means for only alternatively connecting said mechanisms in driving relation with said shaft.
55. In a mining apparatus, a portable support, kerf cutting mechanism carried by said support including a pivoted kerf cutter swingable relative to said support, and motor operated devices for swinging said kerf cutter about its pivot including a drive 100 sprocket, an annular grooved member secured to said kerf cutter, an endless chain engaging said sprocket and guided in the groove on said annular member, and means for connecting said kerf cutter to said endless chain at will.
56. In a mining apparatus, a portable support, kerf cutting mechanism carried by said support including a pivoted kerf cutter swingable relative to said support, and motor operated devices for swinging said kerf cutter about its pivot including a drive 105 sprocket, an annular grooved member secured to said kerf cutter, an endless chain engaging said sprocket and guided in the groove on said annular member, and means for connecting said kerf cutter to said endless chain at will.
57. In a mining apparatus, a portable support, kerf cutting mechanism carried by said support including a pivoted kerf cutter swingable relative to said support, and motor operated devices for swinging said kerf cutter about its pivot including a drive 110 sprocket, an annular grooved member secured to said kerf cutter, an endless chain engaging said sprocket and guided in the groove on said annular member, and means for connecting said kerf cutter to said endless chain at will comprising a chain engaging member carried by said kerf cutter and means for adjusting said member into and 115 out of engagement with said chain.
58. In a mining apparatus, a portable support, kerf cutting mechanism carried by said support including a pivoted kerf cutter swingable relative to said support, and motor operated devices for swinging said kerf cutter about its pivot including a drive sprocket, an annular grooved member secured to said kerf cutter, an endless chain 120 engaging said sprocket and guided in the groove on said annular member, and means for connecting said kerf cutter to said endless chain at will comprising a chain engaging member carried by said kerf cutter and means for adjusting said member into and 125 out of engagement with said chain.
59. In a mining apparatus, a portable support, kerf cutting mechanism carried by said support including a cutter head rotatable about a longitudinal axis and a kerf 130

cutter pivotally mounted on said head for swinging movement relative thereto, and motor operated devices for rotating said cutter head and for swinging said kerf cutter about its pivot including a drive sprocket encircling the head axis, an annular grooved member secured to said kerf cutter, an endless chain engaging said sprocket and guided in the groove on said annular member, means for connecting said kerf cutter to said endless chain, means for locking said kerf cutter head against rotation about its axis, and means for locking said kerf cutter against swinging movement relative to said cutter head.

60. In a mining apparatus, a portable support, kerf cutting mechanism carried by said support including a cutter head rotatable about a longitudinal axis and a kerf cutter pivotally mounted on said head for swinging movement relative thereto, and motor operated devices for rotating said cutter head and for swinging said kerf cutter about its pivot including a drive sprocket encircling the head axis, an annular grooved member secured to said kerf cutter, an endless chain engaging said sprocket and guided in the groove on said annular member, means for connecting said kerf cutter to said endless chain, means for locking said kerf cutter head against rotation about its axis, and means for locking said kerf cutter against swinging movement relative to said cutter head, said kerf cutter locking means comprising an adjustable locking element carried by said kerf cutter and adjustable into and out of engagement with an element of said cutter head.

61. In a mining apparatus, a portable support, kerf cutting mechanism carried by said support including a cutter head rotatable about a longitudinal axis and a kerf cutter pivotally mounted on said head for swinging movement relative thereto, and motor operated devices for rotating said cutter head and for swinging said kerf cutter about its pivot including a drive sprocket encircling the head axis, an annular grooved member secured to said kerf cutter, an endless chain engaging said sprocket and guided in the groove on said annular member, means for connecting said kerf cutter to said endless chain, means for locking said kerf cutter head against rotation about its axis, and means for locking said kerf cutter against swinging movement relative to said cutter head, said means for locking said cutter head against rotation comprising an adjustable element carried by said cutter head and adjustable into and out of engagement with a relatively stationary portion of said support.

62. In a mining apparatus, a portable support having front and rear wheel axles, kerf cutting mechanism carried by said

support including a pivoted kerf cutter movable relative to said support, and motor operated devices for swinging said kerf cutter about its pivot including a rotatable driving element arranged coaxially with one of said wheel axles.

63. In a mining apparatus, a portable support having front and rear wheel axles, kerf cutting mechanism carried by said support including a cutter head rotatable on a longitudinal axis and a pivoted kerf cutter carried by said cutter head and swingable relative thereto, and motor operated devices for rotating said cutter head about its axis including a rotatable driving element arranged coaxially with one of said wheel axles.

64. In a mining apparatus, a portable support having front and rear wheel axles, kerf cutting mechanism carried by said support including a cutter head rotatable on a longitudinal axis and a pivoted kerf cutter carried by said cutter head and swingable relative thereto, and motor operated devices for rotating said cutter head and for swinging said kerf cutter about its pivot including a rotatable driving element arranged coaxially with one of said wheel axles.

65. In a mining apparatus, a portable support, kerf cutting mechanism carried by said support including a cutter head rotatable about a longitudinal axis, and motor operated devices for effecting rotation of said head about its axis comprising a rotatable power operated member surrounding the head axis and a flexible transmission element engaging said member for movement thereby and engaging said head at points offset from its axis of rotation and partially encircling said head axis.

66. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element operatively connectible to said head and kerf cutter to rotate the former and to swing the latter, said kerf cutter being connected to said element at all times during motor operated head rotation by a direct attachment which precludes any relative movement between said element and said kerf cutter, and means for disconnecting said kerf cutter from said element at will.

67. In a mining apparatus, the combination of a body, kerf cutting mechanism including a cutter head mounted on said body for rotation about a longitudinal axis and a kerf cutter pivotally mounted on said head for swinging movement relative ther-

to, and motor operated devices for rotating said head and for swinging said kerf cutter including a common transmission element operatively connectible to said head and kerf cutter to rotate the former and to swing the latter, said kerf cutter being connected to said element by a direct attachment which precludes any relative movement between said element and said kerf cutter and being held stationary relative to said head at all times during motor operated head rotation and means for releasing said kerf cutter therefrom at will.

68. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element operatively connectible to said head and kerf cutter to rotate the former and to swing the latter, said kerf cutter being connected to said element by a direct attachment which precludes any relative movement between said element and said kerf cutter and being held stationary relative to said head at all times during motor operated head rotation, and devices carried by said kerf cutter for disconnecting said kerf cutter from said element and for holding said kerf cutter against swinging movement relative to said head.

69. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element operatively connectible to said head and kerf cutter to rotate the former and to swing the latter, said kerf cutter being connected to said element at all times during motor operated head rotation, said element when so connected being completely immovable relatively to said kerf cutter, and said element having movement relative to said head and kerf cutter while said head and kerf cutter remain stationary.

70. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element operatively connectible to said head and kerf cutter to rotate the former and to swing the latter, said kerf cutter being connected to

latter, said kerf cutter being connected to said element at all times during motor operated head rotation, said element when so connected being completely immovable relatively to said kerf cutter, and means carried by said head for connecting the latter to or disconnecting the same from said element at will. 70

71. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element operatively connectible to said head and kerf cutter to rotate the former and to swing the latter, said kerf cutter being connected to said element by a direct attachment which precludes any relative movement between said element and said kerf cutter and being held stationary relative to said head at all times during motor operated head rotation, and means carried by said head for connecting the latter to or disconnecting the same from said element at will. 80

72. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element operatively connectible to said head and kerf cutter to rotate the former and to swing the latter, said kerf cutter being connected to said element at all times during motor operated head rotation by a direct attachment which precludes any relative movement between said element and said kerf cutter, and devices carried by said cutter head and releasable at will for holding the latter against rotation about its axis during swinging of said kerf cutter. 95 100 105 110

73. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element operatively connectible to said head and kerf cutter to rotate the former and to swing the latter, said kerf cutter being connected to said element at all times during motor operated head rotation, and devices releasable at will for connecting said kerf cutter to said element by a direct attachment which precludes any relative movement between 115 120 125 130

said element and said kerf cutter and for holding said kerf cutter against swinging movement relative to said head during head rotation.

74. In a mining apparatus, the combination of a body, kerf cutting mechanism including a cutter head mounted on said body for rotation about a longitudinal axis and a kerf cutter pivotally mounted on said head for swinging movement relative thereto, and motor operated devices for rotating said head and for swinging said kerf cutter including a common transmission element operatively connectible to said head and kerf cutter to rotate the former and to swing the latter, said kerf cutter being connected to said element at all times during motor operated head rotation, and devices releasable at will for connecting said kerf cutter to said element by a direct attachment which precludes any relative movement between said element and said kerf cutter and for holding said kerf cutter against swinging movement relative to said head during head rotation, said kerf cutter holding devices being released and said cutter head held against rotation about its axis during swinging of said kerf cutter.

75. In a mining apparatus, the combination of a body, kerf cutting mechanism including a cutter head mounted on said body for rotation about a longitudinal axis and a kerf cutter pivotally mounted on said head for swinging movement relative thereto, motor operated devices for rotating said head about its axis including a final transmission element having a pitch line speed appropriate for swinging said kerf cutter at a cutting speed and fixedly connectible to said head to rotate the latter on said longitudinal axis, said element when so connected being completely immovable relatively to said head, and mechanism driven by said transmission element operative when said element is disconnected from said head to effect swinging of said kerf cutter.

76. In a mining apparatus, the combination of a body, kerf cutting mechanism including a cutter head mounted on said body for rotation about a longitudinal axis and a kerf cutter pivotally mounted on said head for swinging movement relative thereto, motor operated devices for rotating said head about its axis including a final transmission element having a pitch line speed appropriate for swinging said kerf cutter at a cutting speed and fixedly connectible to said head to rotate the latter on said longitudinal axis, said element when so connected being completely immovable relatively to said head, mechanism driven by said transmission element operative when said element is disconnected from said head to effect swinging of said kerf cutter, and means for holding said cutter head against

rotation during swinging of said kerf cutter.

77. In a mining apparatus, the combination of a body, kerf cutting mechanism including a cutter head mounted on said body for rotation about a longitudinal axis and a kerf cutter pivotally mounted on said head for swinging movement relative thereto, motor operated devices for rotating said head about its axis including a final transmission element having a pitch line speed appropriate for swinging said kerf cutter at a cutting speed and fixedly connectible to said head to rotate the latter on said longitudinal axis, said element when so connected being completely immovable relatively to said head, mechanism driven by said transmission element operative when said element is disconnected from said head to effect swinging of said kerf cutter, and means for holding said kerf cutter against swinging movement relative to said head during head rotation.

In testimony whereof I affix my signature.

MORRIS P. HOLMES.
